UNITED STATES PATENT OFFICE.

ARTHUR ADDISON YOST, OF BOSTON, MASSACHUSETTS.

BURNER.

Application filed September 21, 1926. Serial No. 136,775.

The invention to be hereinafter described relates to burners of the type in which liquid fuel, such as oil, and an atomizing fluid, such as air under pressure, are fed to a nozzle and on delivery therefrom the air meets the fuel, thereby atomizing the same and promoting the combustion of the fuel.

The aim and purpose of the present invention is to provide an improved burner which will atomize the fuel more thoroughly than heretofore, and produce a flame of proper whirl and spread for efficient combustion and heating effect. The fuel is conducted to a rotary cup which has an outward flaring inner surface to which the liquid fuel clings under the influence of centrifugal force. The atomizing fluid is fed through an annular space between the rotary cup and the nozzle, and on delivery therefrom, meets the fuel.

The present invention provides a series of vanes which are on and project from the rotary cup toward and preferably substantially to the inner surface of the nozzle. The vanes have sufficient length so that they will divide the atomizing fluid into streams and give the same a whirl in a direction different from that of the fuel leaving the cup. The streams of fuel and atomizing fluid are projected in crossing paths, and the fuel is thoroughly atomized.

The cup is rotated by an electric motor, the speed of which can be regulated so that the cup may be rotated at the proper speed for most efficient results. The atomized fluid may be forced to and between the vanes by a fan which is also rotated by the motor. The construction is such that the combustion will occur adjacent to the end of the nozzle and the flame will have a desirable spread enabling it to reach a large area of heating surface.

One good form of the invention is shown in the accompanying drawing, wherein:

Fig. 1 is a view partly in section and partly in side elevation of a burner embodying the invention;

Fig. 2 on an enlarged scale is a side elevation of the rotary cup having the vanes thereon; and

Fig. 3 is a front-end view of the construction shown in Fig. 2.

Referring to the drawing, the embodiment of the invention shown therein comprises a nozzle 1 cylindrical in form having an outstanding flange 3 secured by screw bolts 5

to a fan casing 7. Mounted in the nozzle 1 is a rotary cup 9 having an outwardly flaring interior surface 11. This cup is mounted on one end of a hollow shaft 13 journaled in suitable bearings. The fuel is fed through a pipe 15 from a suitable source of supply, and is delivered to a pipe 17 which extends through the hollow shaft 13 and has a tip 19 adapted to deliver the fuel to the inner flaring surface of the cup. The shaft 13 is directly rotated by an electric motor 21.

A fan 23 in the casing 7 referred to, is mounted fast on the hollow shaft 13, and air may be supplied to the fan through an inlet 25 in the casing 7. The air entering the inlet passes to the fan and is forced thereby into the nozzle and through the annular space between the cup and the inner surface of the nozzle.

Mounted on and projecting outward from the rotary cup are a series of vanes 27 of substantial length and preferably having their outer edges extending substantially to the inner surface of the nozzle. These vanes, in the present instance, are oblique with respect to the axis of rotation of the cup and cooperate with the outer surface of the cup and the inner surface of the nozzle to form a series of passages 29 through which the streams of atomizing fluid will pass. Preferably the outer ends of the vanes are substantially at the delivery end of the nozzle.

The motor rotates the cup in a clockwise direction as indicated by the arrows in Figs. 2 and 3. The liquid fuel delivered to the inner flaring surface of the cup will tend to cling to said surface under the influence of centrifugal force, and will be delivered with a pronounced whirl in a clockwise direction. The atomizing fluid forced by the fan to the nozzle and through the passages between the vanes will be divided thereby into streams which will be given a whirl in a contra-clockwise direction due to the angular disposition of the vanes on the cup and due to the fact that the speed of the motor is such that the fluid is forced through the nozzle between the vanes at a speed much higher than the speed of rotation of the cup.

The fuel and fluid meeting and whirling in opposite directions, thoroughly atomize and break up the fuel, cause efficient combustion and produce a flame of desirable lateral spread which can reach a large heating surface.

The vanes on the rotary cup are solely for the purpose of producing a whirl of the fluid in a direction for promoting efficient combustion of the fuel and producing a flame of 5 the desired character. These vanes are not for causing the rotation of the cup which is produced by and under the control of the electric motor, the speed of which may be varied as desired.

10 It will be understood that the invention is not limited to the specific embodiment shown, and that various deviations may be made therefrom without departing from the spirit and scope of the appended claim.

15 What is claimed is:—

In a burner for atomized liquid fuel, the combination of a casing having a nozzle, a shaft in the casing, a cup in the nozzle on

said shaft, an electric motor for rotating said shaft and cup, whirl promoting vanes 20 of substantial length on and rotative with the cup and projecting out therefrom toward the inner surface of the nozzle, means for delivering atomizing fluid to the passages formed between the vanes, and means to 25 conduct liquid fuel to the cup for delivery therefrom with a whirling motion, said vanes being disposed to divide the fluid into streams, positively whirl said streams with the cup, and discharge the streams in a direction opposite to the direction of rotation of the cup and the fuel leaving the same, thereby effectively to break up and atomize the fuel.

ARTHUR ADDISON YOST.
